UNITED STATES PATENT OFFICE

PERCIVAL S. TICE, OF CHICAGO, ILLINOIS

CARBURETOR

Application filed September 18, 1926. Serial No. 136,251.

The purpose of this invention is to provide an improved construction of a carburetor for internal combustion engines particularly adapted for producing and maintaining the fuel mixture properly proportioned for economy in the ordinary running of the engine both under load and idling, and also adapted to afford prompt acceleration upon change of the throttle opening from idling position or 10 for increased speed at any stage.

It consists in the elements and features of construction shown and described as indicated in the claims.

In the drawings:

15 Figure 1 is a side elevation of an engine equipped with a carburetor embodying this invention for indicating the relative position and mounting of the carburetor with respect to the engine intake manifold.

20 Figure 2 is a section of the carburetor on line 22 in Figures 1, 3, and 5.

Figure 3 is a section axial with respect to the fuel mixture conduit of the carburetor, the float bowl or level-governing chamber being partly broken away.

Figure 4 is a top plan view of the carburetor detached from the engine.

Figure 5 is a staggered section as at the line 5-5 on Figures 2 and 4.

30 Figure 6 is a staggered section at the line 6-6 on Figure 5.

Figure 7 is a detail section at the line 7-7 on Figure 6.

Specific means for effecting the purpose of the invention above stated consists in the employment of two diaphragm pumping devices for injecting excess fuel for acceleration, one of said pumping devices being actuated automatically upon and by means of the change of pressure at the engine intake beyond the throttle resulting from change of throttle opening; and the other being actuated by mechanical connection with the throttle or throttle-adjusting connections, these two pumping devices being brought into action separately or together according to the conditions calling for acceleration, and the rate or degree of acceleration wanted.

In my Patent No. 1,575,877, dated March 50, 1926, I have shown an automatically actu-

ated diaphragm for controlling the opening of a passage for an auxiliary fuel supply for acceleration, said diaphragm having no pumping function. In my pending application Serial No. 16,897, filed March 20, 1925, 55 I have shown the like diaphragm, i. e., automatically actuated, having the added function of pumping the auxiliary fuel supply, i. e., forcing it into the fuel mixture conduit for enriching the mixture. The present 60 invention in one phase of it is differentiated from previous constructions in the provision of an additional diaphragm connected for mechanical actuation for pumping auxiliary fuel. For understanding the principle and 65 mode of operation of the present invention, it should be borne in mind that in general, if the mixture for steady running, that is, for fuel economy as distinguished from the development of maximum power, is comparatively 70 lean, accelerating fuel must be supplied whenever the intake pressure rises appreciably, as upon increased throttling opening or upon increased load slowing down the engine. The primary reason for this need 75 consists in the reduced rate of vaporization at higher intake pressures however caused, and at greater throttling opening, independently of the higher pressures resulting from the greater throttling opening; and the practical 80 problem to be solved is maintenance of effective fuel content in the fuel mixture in the face of vaporization rate reduced by either or both of these causes. The vaporization rate is affected inversely by the 85 change of pressure on the fuel, and other things being equal varies inversely as to pressure. The vaporization rate is affected also by the fineness of the spraying or atomization of the liquid fuel; and since the throttle valve plate itself at all positions except wide open throttle, constitutes the major construction in the path of the injected fuel, and thereby by the means of spraying and mechanically 90 atomizing the jettied fuel, its actual physical 95 position in the passage which it controls strongly affects the degree of atomization and therefore the rate of vaporization of the fuel.

In general, therefore, a greater opening of 100

throttle means both a higher pressure of the fuel at the engine intake and also a reduction of atomization of the fuel by spraying. Both these conditions,—intake pressure and atomization,—are affected by the speed of the engine, in that at lower engine speed the intake pressure may be high with throttle so nearly closed as to have a high measure of effectiveness as a spraying or mechanically atomizing means. For this consideration it will be clear that at lower engine speeds the vaporization rate is maintained at higher fineness for a given intake pressure than at higher speeds, because of the position of the throttle relatively favorable for mechanical atomization by spraying. And it follows that since the vaporization rate is then higher, less extra or auxiliary fuel need be supplied in order to maintain or produce the richness of fuel mixture necessary or desirable for a given change in the intake pressure at the lower as compared with the higher rate of speed.

Since the automatic or pressure-actuated diaphragm pump operates proportionately with the pressure changes without regard to the throttle position, and since a pump mechanically actuated by or from the throttle spindle must operate without regard to the pressure changes, it is clear that neither one alone can be made to serve the requirements to best advantage. The automatic pump, if made of sufficient capacity to deliver the maximum quantity of fuel required upon full acceleration (that is, with wide open throttle), will deliver too much on partial opening of the throttle; and the mechanical pump, if of the same total capacity, would deliver too little fuel on partial opening of the throttle.

These considerations and experimental work based upon them have resulted in a combination in the present construction of the two types of pump device indicated, in which the best possible compromise is believed to have been attained with the automatic pump of a capacity equal to one-half or slightly less than one-half of the total full acceleration or requirement, the remainder being delivered by a mechanically actuated pump discharging proportionately to the angular movement of the throttle spindle or degree of opening of the throttle valve.

The structure shown in the drawings comprises a fuel mixture conduit indicated at 10, level-governing chamber or float bowl indicated at 12, and two diaphragm chambers (hereinafter referred to as variable pressure chambers) 15 and 16, all formed, except as to closure caps and fittings, in a single integral casting, in which the fuel mixture conduit, 10, is substantially vertical, the casting being provided at the upper end of said conduit with suitable flange, 10^a, for securing it at the entrance of the intake manifold of

the engine in a familiar manner. The fuel mixture conduit, 10, is of Venturi form having the air inlet at the lower end and having mounted in its upper end portion a throttle valve, 11. The level-governing chamber, 12, is formed in the casting open at the left hand side, being closed in the final construction by a cap, 13, in which there is formed the fuel inlet shown at 13^a, controlled by the valve, 13^b, operated by the float, 13^c, in the customary construction of carburetor float bowls or level-governing chambers. The said chamber, 12, is situated alongside of the lower or entering end portion of the fuel-mixture conduit, extending up alongside of the neck, 14, which results from the Venturi shape. The diaphragm chambers, 15 and 16, are formed at opposite sides of the neck, 14, as seen most clearly in Figure 2, opening in opposite directions away from the said neck and being closed by the caps, 17 and 18, which secure the diaphragms, 17^a and 18^a, which form the movable walls of the chambers and by means of which they function as variable capacity chambers.

For the mode of operation and functioning of this carburetor it is constructed with three substantially independent fuel passages leading from the level-governing chamber, which constitutes the immediate fuel source, for discharge into the fuel mixture conduit, 10, said discharge of all three of the passages being substantially at the flow-accelerating constriction or throat of the venturi, and as shown, through the same jet port or nozzle. The first to be described of these fuel passages will be referred to as the "principal fuel passage" which may be traced in the drawings from the level-governing chamber, 12, to the passage at the Venturi throat, as comprising the metering orifice, 20^a, in the metering plug, 20 (see Figure 3), the bore, 21, extending longitudinally with respect to the fuel mixture conduit, and a transverse bore, 22, discharging in the Venturi throat at the jet port or nozzle, 23, as seen in Figure 3. The second of these fuel passages, which will be referred to as the "secondary passage" may be traced from the level-governing chamber, 12, as comprising the port, 30 (see Figure 2), opening into the passage, 31, from which the port, 32, in the inner end of the sleeve, 33, leads through said sleeve to the port, 34, opening laterally therefrom into the variable capacity chamber, 15, bounded by the diaphragm, 17^a, from which variable capacity chamber the port, 35 (see Figure 6), leads to a check valve chamber, 36, which opens by a port, 37, into a bore, 38, which intersects the bore, 22, and for discharge at the jet port or nozzle, 23. This secondary passage has an additional connection at its initial part for leading from the level-governing chamber to the variable capacity chamber, 17, consisting in the metering orifice, 30^a, formed in the metering plug,

30^b (see Figure 2 and Figure 6), leading into the variable capacity chamber, 15. The service performed by the two independent leads from the level-governing chamber, 14, to the variable capacity chamber, 15, is fully set forth in my pending application Serial No. 16,897, filed March 20, 1925.

The third fuel passage from the level-governing chamber to the fuel mixture conduit 10 will be referred to as an "auxiliary passage" and may be traced from the level-governing chamber as comprising check-valve-controlled-passage, 40, in the metering plug, 40^a, which leads into the variable capacity chamber, 16 (see Figure 2 and Figure 6), from which chamber the passage leads by way of the port, 42, into check valve chamber, 43, which at the opposite side of the check valve, 43^a, opens into the bore, 38 (see Figure 6 and Figure 7), which intersects the bore, 22, for discharge at the jet port or nozzle, 23.

The specific purposes and mode of operation of these different fuel passages will be hereinafter explained.

For two distinct purposes there is provided a passage leading from a point in the fuel mixture conduit beyond the seating position of the throttle valve, 11, comprising (see Figure 3) a port, 50, and a bore, 51, into which it leads. For one of the purposes which it is provided this bore, 51, intersects the bore, 52, which leads to a reduced bore, 53, which communicates with the bore, 22, of the principal fuel supply passage. The bore, 52, is formed 25 through a boss, α , for mounting a needle valve, 60, whose tapered terminal seats at the entrance to the reduced passage, 53, said valve being provided exteriorly with a handle, 61, for manual operation and with a check 30 device, 62, for retaining it at any desired position of adjustment for controlling the degree of opening of the needle valve. For a second purpose of the passage, 51, it communicates with a bore, 64, which intersects the bore, 52, back of the seat of the needle valve, 60, said bore, 64, leading by way of a bushing, 65 (see Figure 6) through the diaphragm, 17^a, which constitutes the movable wall of the variable capacity chamber, 15, into the chamber, 17^a, formed in the diaphragm-securing cap, 17, hereinafter referred to as a pressure chamber.

It will be understood that the several bores forming by their intersections the continuous passages described, from the level governing chamber to the points of discharge in the fuel mixture conduit, are formed so as to thus intersect and connect for continuity, by boring in from convenient points in the exposed surface of the casting in the proper directions for thus meeting and intersecting, the outer ends of the bores being closed by suitable plugs as shown in the drawings and requiring no detail description in order to be understood.

One function of the passage, 51, leading

from beyond the throttle valve to the discharge bore, 22, of the principal fuel passage, is the familiar one of constituting an "idling by-pass" for fuel which will be drawn by engine suction through said duct, 51, when the throttle valve is adjusted at idling position, 70 nearly closed, the supply thus drawn, which is limited by the adjustment of the needle valve, 60, sufficing for keeping the engine running idle or under light load. In the 75 present construction without defeating or in any manner or degree interfering with this function, the passage, 51, is utilized by means of the intersecting bore, 64, for an independent function, namely, admitting or transmitting pressure of varying degree to the pressure chamber, 19, for operating the diaphragm, 17^a, which constitutes the movable wall of the variable capacity chamber, 15, for reducing the capacity of that chamber for the 80 purpose of ejecting fuel therefrom through the passage leading from it and discharging in the fuel mixture conduit, in addition to the normal fuel supply discharged simultaneously at the same point derived through the metering plug, 20, and bore, 21, drawn by the suction operating directly through the fuel mixture conduit at the Venturi throat. This action occurs when the engine, having 85 been idling or running under light load or at relatively low speed, the throttle opening is increased for starting the vehicle from rest or for increasing speed. Such increased opening of the throttle causes increased pressure in the intake passage immediately beyond the throttle, which increased pressure operating on the diaphragm, 17^a, forces it inward with respect to the chamber 15; or, as the action might be described, the diminished suction permits the spring, 25, which is positioned for acting on the diaphragm in the direction for contracting the chamber, 15, to act with less restraint for reducing the chamber, 15; and that chamber being normally full of liquid fuel because it is wholly below the governed level (indicated by the line, $x-x$, in Fig. 4) of the level-governing chamber, 12, forces liquid fuel in a jet through the port, 23, into the fuel mixture conduit, momentarily enriching the mixture and causing instant and momentary acceleration of the 100 engine. This effect, it will be understood, 105 lasts only for the period during which the pressure above the throttle valve is increasing; and the diaphragm, 17^a, coming to rest at the somewhat advanced position which causes reduced capacity of the chamber to the extent of the amount of fuel ejected, the fuel mixture proportions will return to the normal as determined by the construction in respect to dimensions and arrangement of the 110 Venturi passage and principal supply duct.

The passage, 51, with its connection at 50 beyond the throttle, beside the function already described, serves incidentally a third 115

purpose at certain stages and conditions of engine action, by reason of the reduced bore, 53, through which the duct, 51, communicates as described with the fuel passage, 21, 5 22, just before the passage at 23 into the fuel mixture conduit, namely, that upon increase of pressure at 50 resulting from the opening of the throttle after the engine has been idling, the fuel which has been drawn into the passage, 51, during idling is forced back and discharged in a jet through the reduced port, 53, with an aspirating effect supplying instantly, and in the interval which will lapse before the supply would normally come 10 through the passage, 21, 22, and the port, 23, the added fuel required to maintain fuel mixture at proper richness for operating the engine running with open throttle.

The purpose of the third or "auxiliary" 20 fuel passage described is to afford an auxiliary jet of fuel to be delivered by action of the diaphragm, 18^a, in the same manner as the fuel jet is delivered through the secondary passage by the action of the diaphragm, 17^a, 25 the diaphragm pressure for delivering the jet to the auxiliary passage being produced by mechanical connection from the throttle valve, this connection being such as to operate the diaphragm for pressure upon the movement of the throttle valve from a predetermined closed or partially open position for a predetermined distance and through a predetermined angle or distance of opening. Specifically, the desirable construction is that 30 the diaphragm is operated for following up the initial movement of the throttle valve from idling position (closed or nearly closed), for a fraction only of full opening. The construction for this purpose consists in providing 35 at one protruding end of the throttle valve stem, 80, a cam, 81, whose cam protrusion, 81^a, cooperates with the terminal abutment, 82^a, of a lever, 82, fulcrumed at the upper corner of the cap, 18, of the diaphragm chamber, 16, and having at its lower end an abutment, 82^b, operating against the protruding end of the stem, 18^c, of the diaphragm, 18^a. It will be understood that upon rotation of the throttle valve stem, the cam, 40 81^a, will cause the lever, 82, to be rocked in the direction for thrusting inwardly the diaphragm stem, 18^c, thereby causing the movement of the diaphragm for reduction of the variable capacity chamber, 16, which will 45 impel the liquid contents of that chamber through the auxiliary fuel passage described and cause the delivery of a jet of fuel through the duct, 22, for discharge at the port, 23, into the fuel mixture conduit at the Venturi throat.

The specific construction of the parts through which the secondary fuel passage is formed leading from the port, 30, to the variable pressure chamber, 15, comprising the 50 sleeve, 33, having the valve port, 32, co-

operating with the valve, 32^a, positioned within the sleeve, is for a specific purpose fully set forth in my co-pending application Serial No. 16,897, filed March 20, 1925, and need not be further described here beyond pointing out that the sleeve, 33, is pressed into contact with the diaphragm, 17^a, for movement therewith, the valve, 32^a, being seated, not by its own movement, but by the movement of the sleeve, and that this valve is held in position longitudinally by the thrust of the spring, 33^a, reacting for thrusting it in the direction for seating at the port, 32, the valve being stopped as to movement in that direction by a screw, 33^c, which is set through the neck, 14, and is suitably adjusted in the assembling of the structure to determine the distance of movement of the diaphragm, 17^a, from normal rest position shown in Figure 2 necessary to seat the valve, 32^a; and it will be seen that in further movement of the diaphragm in that direction the valve will be withdrawn with the sleeve while held seated by the spring. The reason for providing two paths for the liquid from the chamber, 12, 55 to the variable pressure chamber, 16, one through the port, 30, and the subsequent passages mentioned, and the other through the metering plug, 23, is fully set forth in my co-pending application and is not a part of the present invention and need not be further stated here.

It will be obvious that means for mechanically, at will, operating the diaphragm, 18, may be substituted for the cam-connection with the throttle valve, and my invention in respect to auxiliary fuel supply at will is not limited to means for causing it associated with the throttle valve adjustment.

I claim:

1. In a carburetor and the like for an internal combustion engine in combination with an air and fuel mixture conduit adapted to be connected for discharge at the engine intake, a throttle valve in said conduit; a level-governing chamber constituting an immediate source of liquid fuel, and a principal fuel supply passage leading therefrom for discharge in the fuel mixture conduit anterior to the throttle valve, comprising in its course a flow restricting means and another fuel passage leading from the level-governing chamber for like discharge, and intermediately by-passing said flow-restricting means of the principal fuel passage and a third fuel passage also leading to like discharge; variable capacity chambers interposed in and constituting a part of said second and third fuel passages respectively, having movable walls for varying their capacity; 105 mechanical connections from the throttle valve for actuating the movable wall of the variable capacity chamber in one of said additional fuel passages, and fluid pressure connections from beyond the throttle for ac- 110

tuating the movable wall of the variable capacity chamber in the other of said additional fuel passages.

2. In a carburetor and the like for an internal combustion engine in combination with an air and fuel mixture conduit adapted to be connected for discharge at the engine intake; a throttle valve in said conduit; a level-governing chamber constituting an immediate source of liquid fuel and a principal fuel supply passage leading therefrom for discharge in the fuel mixture conduit; a secondary fuel passage leading from the fuel source for discharge in said conduit, a variable capacity chamber interposed and constituting a part of said secondary passage intermediate the fuel source and the discharge of said passage in the fuel mixture conduit; means for restricting the flow 10 through said secondary passage toward said variable capacity chamber, the capacity-varying means comprising a movable wall of said chamber, a pressure chamber opposite said wall and a pressure duct leading from a point in the fuel mixture conduit beyond the throttle valve to said pressure chamber, whereby increase of pressure in the engine intake passage beyond the throttle valve tends to reduce said variable capacity chamber and impel fuel therefrom through said secondary passage for discharge in the fuel mixture conduit, a check valve intermediate said variable capacity chamber and the discharge 15 of said passage, opening in the direction for such discharge and seating in the opposite direction; an auxiliary fuel passage leading from the fuel source for discharge in the fuel mixture conduit, comprising a second variable capacity chamber having for varying its capacity a movable wall, and operating connections from the throttle valve for moving said wall in the direction for reducing the capacity of said chamber for forcing fuel through said auxiliary passage for discharge 20 in the fuel mixture conduit upon movement of the throttle valve in the direction for increased opening.

25 3. In a carburetor and the like for an internal combustion engine in combination with such a point in the fuel mixture conduit beyond the throttle valve to said pressure chamber, whereby increase of pressure in the engine intake passage beyond the throttle valve tends to reduce said variable capacity chamber and impel fuel therefrom through said secondary passage for discharge in the fuel mixture conduit, a check valve intermediate said variable capacity chamber and the discharge of said passage, opening in the direction for such discharge and seating in the opposite direction; an auxiliary fuel passage leading from the fuel source for discharge in the fuel mixture conduit, comprising a second variable capacity chamber having for varying its capacity a movable wall, and operating connections from the throttle valve for moving said wall in the direction for reducing the capacity of said chamber for forcing fuel through said auxiliary passage for discharge 30 in the fuel mixture conduit upon movement of the throttle valve in the direction for increased opening.

35 4. A fuel mixture forming and delivering device for an internal combustion engine, adapted to be connected for delivering fuel mixture at the engine intake, comprising a fuel mixture conduit; a throttle valve therein; a fuel source constructed for maintaining the fuel at a governed level; a passage for leading liquid fuel from the fuel source to a point of discharge in the fuel mixture conduit anterior to the throttle; a duct extending from a point in the fuel mixture conduit beyond the throttle valve to a point of communication with said fuel passage immediately preceding the discharge of the latter into the fuel mixture conduit, said last mentioned duct being reduced to form a jet at its discharge; whereby said duct serves upon increase of throttle opening after closure to idling position as a gas pressure duct for delivering an aspirating jet into the fuel passage substantially at its discharge into the fuel mixture conduit, the fuel passage mentioned being a principal fuel supply passage; an auxiliary fuel passage leading from the fuel source for discharge in the fuel mixture conduit through the final discharge portion of said principal fuel passage; a variable capacity chamber having a portion of its enclosing wall movable for varying its capacity 40 and connections from said throttle valve operating means for moving said wall upon movement of the throttle valve in the direction for opening, whereupon upon such opening movement an accelerating jet of fuel is

driven through said auxiliary passage exposed to an aspirating jet delivered through the pressure passage.

5. In a carburetor and the like for an internal combustion engine in combination with an air and fuel mixture conduit adapted to be connected for discharge at the engine intake; a throttle valve in said conduit; a level-governing chamber constituting an immediate source of liquid fuel, and a principal fuel supply passage leading therefrom for discharge in the fuel mixture conduit; a secondary fuel passage leading from the fuel source for discharge in said conduit; a variable capacity chamber interposed in and constituting a part of said secondary passage intermediate the fuel source and the discharge of said passage in the fuel mixture conduit, the capacity-varying means comprising a movable wall of said chamber, a pressure chamber opposite said wall and a pressure duct leading from a point in the fuel mixture conduit beyond the throttle valve to said pressure chamber, whereby increase of pressure in the engine intake passage beyond the throttle valve tends to reduce said variable capacity chamber and impel fuel therefrom through said secondary passage for discharge in the fuel mixture conduit, a check valve intermediate said variable capacity chamber and the discharge of said passage, opening in the direction for such discharge and seating in the opposite direction; an auxiliary fuel passage leading from the fuel source for discharge in the fuel mixture conduit, comprising a second variable capacity chamber having for varying its capacity a movable wall, and operating connections from the throttle valve for moving said wall in the direction for reducing the capacity of said chamber for forcing fuel through said auxiliary passage for discharge in the fuel mixture conduit upon movement of the throttle valve in the direction for increasing opening.

6. In a carburetor and the like for an internal combustion engine in combination with an air and fuel mixture conduit adapted to be connected for discharge at the engine intake; a throttle valve in said conduit; a level-governing chamber constituting an immediate source of liquid fuel and a principal fuel supply passage leading therefrom for discharge in the fuel mixture conduit; a secondary fuel passage leading from the fuel source for discharge in said conduit, a variable capacity chamber interposed in and constituting a part of said secondary passage intermediate the fuel source and the dis-

charge of said passage in the fuel mixture conduit, the capacity-varying means comprising a movable wall of said chamber, a pressure chamber opposite said wall and a pressure duct leading from a point in the fuel mixture conduit beyond the throttle valve to said pressure chamber, whereby increase of pressure in the engine intake passage beyond the throttle valve tends to reduce said variable capacity chamber and impel fuel therefrom through said secondary passage for discharge in the fuel mixture conduit, a check valve intermediate said variable capacity chamber and the discharge of said passage, opening in the direction for such discharge and seating in the opposite direction; an auxiliary fuel passage leading from the fuel source for discharge in the fuel mixture conduit, comprising a second variable capacity chamber having for varying its capacity a movable wall, and operating connections from the throttle valve for moving said wall in the direction for reducing the capacity of said chamber for forcing fuel through said auxiliary passage for discharge in the fuel mixture conduit upon movement of the throttle valve in the direction for increasing opening.

In testimony whereof, I have hereunto set my hand at Chicago, Illinois, this 13th day of September, 1926.
